DI9768

UNITED STATES PATENT OFFICE.

HENRY CLAY BASCOM, OF LANSINGBURG, AND FRANCIS RITCHIE, OF TROY,
ASSIGNORS TO THE SIMONDS MANUFACTURING COMPANY, OF NEW
YORK, N. Y.

DESIGN FOR A HEATING-STOVE.

SPECIFICATION forming part of Design No. 19,768, dated April 22, 1890.

Application filed March 15, 1890. Serial No. 344,055. Term of patent 7 years.

To all whom it may concern:

Be it known that we, HENRY CLAY BASCOM and FRANCIS RITCHIE, citizens of the United States, residing in the county of Rensselaer 5 and State of New York, the said BASCOM at the village of Lansingburg and the said RITCHIE at the city of Troy, have invented and produced a new and original Design for Stoves, of which the following is a specification, reference being had to the accompanying drawing, forming a part thereof, and consisting of a single figure affording a view in perspective of our newly-designed stove.

We embody our design in a heating-stove 15 having approximately the cross-sectional form of a trapezoid through its various horizontal planes, the line formed by the front side of the stove being parallel with the back side, but a little shorter, the other two sides or 20 ends converging equally toward the front side, to which they are joined by rounded corners. The top plate of the stove is surrounded by an ornamental dome or cover having its plan outlines approximately semi-elliptical in form, the straight side being in the 25 same vertical plane with the back side of the stove; and the invention consists in the conformation and ornamentation substantially as illustrated and herein described and 30 claimed.

A represents the front side of the stove, and A' the contiguous sides, which are substantially alike in form and ornamentation, and may be called the "ends."

A² is the ash-pit section, which is surrounded on three sides, at the bottom, by a horizontal projecting base A³, outlined by the plain edge A⁴.

Midway of the base-plate, on the front side, 40 is an ornamental figure A⁵, consisting of a conventionalized lotus between two scrolls with honeysuckle terminals. At either side of the central figure is a foliated wave-line rib, terminating near each front corner of the stove 45 in a scroll.

On the base-plate, at the ends of the stove, are a series of connected foliated wave-lines with scroll terminals.

The top B' of the ash-pit section separates 50 that section from the fire-box section B, and consists of a convexed shelf-like projection extending horizontally along the front and

converging sides, ornamented with a beaded outer border B², separated by a plain band B³ from its inner border, which is ornamented 55 by foliated wave-line ribs with scroll terminals.

The fire-box section is separated from the illuminating-section C by the horizontal beaded border C'.

The doors C² of the illuminating and fire-box sections are ornamented by the vine-like scrolls C³, having scroll-shaped branches and surrounding the mica openings C⁴.

The top D has an inner border D' with an 65 unornamented inclined surface, and an outer border D² with a convex unornamented surface, inclosing between such borders an ornamented band extended horizontally along the 70 front and converging sides of the stove, and having in the front part of the band the letters "Crest." Surmounting the top is a dome or cover E, semi-elliptical in plan outline, and having around the curved portion of its base two horizontal rows E' of small openings, one 75 above the other, the individual openings in the upper row being egg-shaped and those in the lower row tongue-shaped, also a plain band E² extending horizontally around the dome above the upper row of openings, and 80 ornamental foliated scrolls in the space between the band and row of openings and extending from such band to the apex of the dome.

Having thus described our new design, what 85 we desire to claim and secure by Letters Patent is—

1. The design for a stove herein shown and described, consisting of an ash-pit section having an ornamented horizontally-projecting base, a fire-box section above the ash-pit section and separated therefrom by an ornamented convexed shelf-like projection, an illuminating-section above the fire-box section, and an ornamented convexed top surmounted 95 by a semi-elliptical dome, the cross-sectional form on horizontal planes of all the parts named, except the dome, being that of a trapezoid, with the front and back sides parallel and the other two sides or ends converging 100 equally toward the front side.

2. In a design for a stove, the ornamental design for an ash-pit base, consisting of a central lotus and honeysuckle figure on the side

- projecting from the front of the stove between two foliated wave-line ribs terminating near each front corner of the stove in a scroll form, substantially as shown and described.
- 5 3. In a design for a stove, the design for an ash-pit top, consisting of a convexed shelf-like projection on the front and ends of the stove, having a ribbed outer border and an inner border ornamented by foliated wave-line ribs 10 with scroll terminals, substantially as described and shown.
4. In a design for a stove, the design for a stove-door, consisting of the vine-like scrolls having scroll-shaped branches and surrounding the mica openings, substantially as described and shown.
- 15 5. In a design for a stove, the design for a top, consisting of an inner border with an unornamented inclined surface and an outer border with a convex unornamented surface 20 inclosing an ornamented band extending horizontally along the front and ends of the stove,

and having in the front part the letters "Crest," substantially as described and shown.

6. In a design for a stove, the design for a dome, consisting of two horizontal base-rows of small openings, one above the other, the individual openings in one row being egg-shaped and those in the other row being tongue-shaped, a plain band extending horizontally around the dome above the upper row of openings, and ornamental foliated scrolls in the space between the band and row of openings and between such band and the apex of the dome, substantially as described and shown.

In testimony whereof we have hereunto set our hands this 3d day of March, 1890.

HENRY CLAY BASCOM.
FRANCIS RITCHIE.
